CONTROL SYSTEM

Filed Aug. 10, 1939

FIG. 2.

UNITED STATES PATENT OFFICE

2,273,126

CONTROL SYSTEM

Howard O. McGillin, Philadelphia, Pa., assignor
to The Brown Instrument Company, Philadelphia, Pa., a corporation of Pennsylvania

Application August 10, 1939, Serial No. 289,340

7 Claims. (Cl. 22—89)

The present invention relates to a system of controlling temperatures and more particularly to a system of measuring and controlling the temperature of a body of material as it is being moved from one point to another.

It is an object of the present invention to measure a condition of a body of material as it is being transported and as a result of this measurement to control the application of a condition changing medium thereto.

It is a further object of this invention to control the temperature of sand used for the making of moulds as it is being taken from a storage bin to a point of use.

It is still a further object of my invention to control the supply of a material to a conveyor belt in response to the temperature of the material passing a given point.

In various foundries it is the practice to empty the sand used in moulds in a storage bin, and convey it from this bin as it is needed to a point of reuse. As the sand may be at a temperature of from anywhere between room temperature to a thousand degrees or so, depending upon how recently it has been used, some means is necessary to bring the temperature down to a point at which the sand may be conveniently handled. On the other hand if the sand is too cool it has to be reheated before use, so there is an optimum temperature which it is desirable to maintain. The apparatus of the present invention is designed to measure the temperature of the sand as it is moving past a point and to control the application of a cooling spray thereto in response to its temperature.

While I will describe my invention as being used in the control of sand temperatures, it will be obvious that the system is equally applicable in the control of any material that is being handled, and that the system may be used to raise the temperature of as well as to cool the material.

The various features of novelty which characterize my invention are pointed out with particularity in the claims annexed to and forming a part of this specification. For a better understanding of the invention, however, its advantages and specific objects obtained with its use, reference should be had to the accompanying drawing and descriptive matter in which I have illustrated and described a preferred embodiment of the invention.

In the drawing:

Fig. 1 is a view of the component parts of my control system; and

Fig. 2 is a diagrammatic view of a control instrument used in the system.

As sand that has been used for moulds is removed from the castings it is stored in a bin 1 until such time as it is again needed. This sand is usually at a very high temperature when it is put in the bin and if it is to be used again soon some means has to be provided to cool it. From the bin 1 the sand falls on a metal conveyor belt 2 passing over rollers 3 one of which is driven by a motor 4. From the belt 2 the sand is dropped on a rubber belt 5 and conveyed to the point of reuse. If its temperature is above 200° F. the conveyor belt 5 will be damaged, but if it is much below this temperature it must be reheated before it can again be made into moulds. Therefore, the apparatus now to be described is adjusted to lower the sand temperature if it is above the danger point and to perform no operation thereon if it is below said point.

Upon leaving the storage bin 1 on the belt 2 the sand first passes under a roller 6 mounted on a support 7 that is pivoted at 8. Movement of this support 7 controls a switch 9 that, with a temperature responsive switch 10, is in circuit with the coil 11 of a solenoid valve 12 in a supply line 13 for cooling water that is to be sprayed upon the sand. The arrangement is such that if no sand is on the belt 2 the roller 6 will be lowered to the position shown to open switch 9 and deenergize the coil 11 to permit valve 12 to close and stop the flow of the cooling water.

Beyond the roller 6 the sand moves past a thermocouple 14 that is responsive to its temperature, the thermocouple being connected to a potentiometric measuring and control instrument 15 which is used to adjust the opening of an air operated valve 16, also in the pipe 12. Beyond the valve 16 the pipe 12 extends into a shielding box-like structure 17 and terminates in a spray-head 18 that is adapted to discharge liquid on the sand.

The instrument 15 is preferably an air control potentiometer of the type described in detail in Harrison Patent 2,112,091, issued March 22, 1938. For purposes of illustration herein, however, it is diagrammatically shown in Fig. 2 as comprising an ordinary null-point potentiometric circuit in which the voltage of the thermocouple 14 is impressed across a portion of a resistor 19 in opposition to the known and constant voltage of a battery 20. Located in series with the thermocouple is a galvanometer 21 whose pointer 22, will deflect in one direction or the other depend-

ing upon whether the voltage drop of the thermocouple across that portion of the resistor 19 between its left end and contact 23 is more or less than that of the battery 20.

As the galvanometer pointer 22 deflects in response to changes in the thermocouple voltage and sand temperature it will engage either contact 24 or 25 to energize a reversible motor 26 for rotation in one direction or the other. The motor 26 is connected to drive a threaded shaft 27 to shift a pen carriage 28 along a chart 29 to make a record of the sand temperature. The carriage 28 carries the contact 23 to move the said contact along the resistance 19 in a direction to rebalance the potentiometer circuit and cause pointer 22 to return to its mid-position and open the motor circuit.

Also carried on the pen carriage 28 is a roller 30 which, upon movement of the carriage to some predetermined low position engages the cam edge of a support 31 upon which the switch 10 is mounted to tilt that support around its pivot 32 against the bias of spring 33 to open that switch and permit the closing of valve 12. Thus when the sand reaches a predetermined low temperature the supply of cooling fluid in pipe 13 is cut off.

Opening and closing of valve 16 is also accomplished by movement of the pen carriage by means of a cam 34 carried thereby. As the pen carriage moves down scale or to the left for example, the cam 34 forces a lever 35, pivoted at 36, downwardly so that a pin 37 extending from its lower end recedes from a flapper valve 38. This valve 38 is pivoted at 39 and has a natural bias toward the restricted open end of a pipe 40 which is supplied with air at a suitably regulated pressure, past a restriction 41. A branch 42 of the pipe is connected with a chamber of the valve 16 and above a diaphragm located therein. Therefore as the pen carriage moves down scale the flapper 38 will move nearer to and restrict the leakage through the end of pipe 40. Air pressure will accordingly be built up in that pipe and branch 42 to be applied to the diaphragm of valve 16 to close the valve. In a similar manner movement of the pen carriage up scale will permit the lever 35 to rise under the bias of spring 43 and cause pin 37 to move flapper 38 away from the end of pipe 40. This will permit air to more readily escape therefrom, reducing the pressure on its diaphragm so that the valve 16 may open and supply water to the spray head 18.

If, for some reason, the spray from head 18 was not sufficient to reduce the temperature of the sand below the danger point or if the supply of water thereto was discontinued the belt 5 would be injured or destroyed unless a safety device similar to the one now to be described was provided to prevent hot sand from being dropped upon that belt. In the path of the sand on belt 2 beyond the shielding structure 17 is located a bulb 44 that is filled with some suitable temperature responsive substance that upon heating thereof will expand and elongate a bellows element 45. This element along with a pivoted switch support 46 and a mercury switch 47, is located in a casing 48. When the temperature of the sand passing the bulb 44 is too high the bellows 45 will expand and move support 46 around its pivot to close the switch 47 which is in a circuit containing a signal 49 and the coil 50 of a switch 51. Thus when switch 47 is closed the signal 49 will be energized to indicate either

audibly or visually or both that the sand temperature is too high and the switch 51 will be opened against the bias of a spring 59. Opening of the switch 51 deenergizes the drive motor 4 and a coil 53, which through its core member maintains a closure member 54 for the bin 1 open against its closing tendency that is provided by the spring 55. A switch 56 is provided in the motor line to shut down the system manually when desired.

A general summary of the operation of this system will now be given. Upon closure of the switch 56 which sets motor 4 in operation the belt 2 will start moving to deliver sand to the belt 5. If no sand is going from the bin 1 the roller 6 will be in engagement with the belt 2 and the switch 9 will be open thus deenergizing coil 11 and permitting valve 12 to close to shut off the supply of water. When sand starts to be carried along the belt 2, the roller 6 will be lifted and switch 9 closed and if the temperature of the sand is below the danger point switch 10 will also be closed to energize coil 11 and open valve 12 so that water can be supplied to spray edge 18 as required by the valve 16. As the temperature of the sand varies the cam 34 of the instrument 15 will be moved relative to the lever 35 and thereby move flapper 38 with respect to the restricted end of pipe 40. Such movement will vary the air pressure applied to the diaphragm of valve 16 so that valve will be opened and closed in an amount proportional to the temperature of the sand thus controlling the proper amount of cooling water to be sprayed on the sand as it is carried beneath the structure 17.

If for some reason the water sprayed upon the sand should not be sufficient to cool it below the danger point the bulb 44 will be heated and thereby cause expansion of the bellows 45 to close switch 47. This will cause the signal to be given by 49 indicating that the temperature of the sand is too high and will simultaneously open switch 51 in the circuit of motor 4 to stop the belt 2. At the same time the coil 53 will be deenergized so that spring 55 can move the closure member 54 to cut off the supply of sand to the belt 2.

From the above detailed description it will be seen that I provided a control system whereby the temperature of a material that is being conveyed past a point may be automatically controlled at will. I have also provided a safety device which will prevent damage to any subsequent apparatus with which the material whose temperature is being controlled may come in contact.

While I have described my invention as being used to lower the temperature of sand I do not wish to be limited thereto, since it will be obvious from the description that my control system may be used to control the temperature of any material that is being moved past a point and it will also be obvious that some heating medium instead of a cooling medium may be supplied if so desired.

While in accordance with the provisions of the statutes, I have illustrated and described the best form of my invention now known to me, it will be apparent to those skilled in the art that changes may be made in the form of the apparatus disclosed without departing from the spirit of my invention as set forth in the appended claims, and that in some cases certain features of my invention may sometimes be used to ad-

vantage without a corresponding use of other features.

Having now described my invention, what I claim as new and desire to secure by Letters Patent is:

1. In a system for controlling the temperature of a material, the combination with means to convey the material through a path, means located adjacent said path responsive to passage of said material, a valve operated thereby to control the supply of a temperature changing medium to be applied to said material, separate means in proximity to the material and responsive to its temperature to adjust said valve and therefore said supply of temperature changing medium in accordance therewith, and other means also in proximity to said material and responsive to a predetermined temperature thereof to stop the supply of said material on said conveying means.

2. In a system of the class described the combination with means to convey material to be treated through a path, mechanism to control the supply of a condition changing medium to be applied to said material, means located along said path responsive to the passage of said material, means located along said path responsive to a condition of said material cooperating with said second means to control said mechanism, and other means controlled by said last named means alone to adjust the mechanism and therefore the supply of the condition changing medium in response to a condition of said material.

3. In a control system, means to convey material to be treated from a point of supply through a path, means to control the temperature of said material, means responsive to the temperature of said material to regulate said control means and separate means in said path beyond said control means responsive to a predetermined temperature of the material to stop the supply of said material to said control means.

4. In a control system means to convey material from a point of supply through a path, means to regulate a supply of a condition changing medium to act on said material as it passes through said path, means adjacent said material and responsive to its passage and means in the path of said material as it travels responsive to

a predetermined low temperature thereof to adjust said regulating means and stop the supply of said condition changing medium and means also in the path of said material responsive to a second predetermined temperature thereof to stop the supply of said material on said conveying means.

5. In a control system for controlling the temperature of a material moving from a point of supply through a path, means to regulate a supply of temperature changing medium to be applied thereto, means to continuously measure the temperature of said material and means responsive to the temperature measuring means to control the regulating means and therefore the application of said temperature changing medium to said material, means actuated upon discontinuance of the material to adjust said regulating means to cut off the supply of the temperature changing medium and means responsive to failure of the supply of the temperature changing medium to cut off the supply of material.

6. In apparatus to condition sand for use in moulds, the combination for a bin with a supply of sand, of means to convey sand from the bin to a point of use, means to regulate a source of temperature changing medium, means responsive to the passage of sand on said conveying means past a point to control said regulating means and therefore the application of said temperature changing medium from said source, and means responsive to the temperature of the sand to adjust the regulating means to adjust the volume of the temperature changing medium applied thereto.

7. In apparatus to condition sand for use in moulds, a storage bin for the sand, means to convey the sand from the bin to a point of use, a valve to regulate a supply of cooling water for the sand, means responsive to the temperature of the sand on the conveyor to regulate the valve, a temperature responsive element in the path of the sand after it has been treated by the water, and means actuated by said temperature responsive element upon a predetermined high temperature of the sand to cut off the supply thereof from the bin and stop the conveyor.

HOWARD O. McGILLIN.
